WELDER'S HELMET OR SIMILAR ARTICLE

Marshall N. Anderson, Grayslake, Ill., assignor to
Sellstrom Manufacturing Company, Palatine, Ill.

Filed June 1, 1964, Ser. No. 80,230

The portion of the term of the patent subsequent to
Sept. 9, 1982, has been disclaimed

Term of patent 14 years

Int. Cl. D2—03

U.S. Cl. D2—232

FIG. 1 is a top plan view of a welder's helmet or similar article showing my new design;

FIG. 2 is a front elevational view of a welder's helmet or similar article shown in FIG. 1; and

FIG. 3 is a side elevational view taken from the left of FIG. 2.

The essential features of my new, original and ornamental design for a welder's helmet or similar article resides in the particular upper crown portion thereof which is shown associated with a depending face mask portion.

The inner surface of the welder's helmet or similar article follows the contour of the outer surface thereof as shown in the drawing.

I claim:

The ornamental design for a welder's helmet or similar article, substantially as shown and described.

No references cited.
